Company, Chicago, Ill., a corporation of Illinois

Application March 2, 1946, Serial No. 651,648

13 Claims. (Cl. 225—21)

1
This invention relates to a beverage dispenser, and more particularly to a dispenser adapted to dispense and mix beverage syrup and carbonated water and to discharge the resulting mixture.

Among the several objects of this invention may be noted the provision of a beverage dispenser comprising a syrup dispenser and a carbonated water faucet adapted to direct a stream of carbonated water toward a stream of syrup flowing from the syrup dispenser; the provision, in such a beverage dispenser, of an improved syrup tank having an improved syrup dispensing valve and means for facilitating proper setting of the valve to dispense the proper amount of syrup regardless of the level of syrup in the tank; the provision, in such a beverage dispenser, of an improved carbonated water outlet adapted to discharge carbonated water over syrup flowing from the syrup tank without excessive loss of carbonation; and the provision of a beverage dispenser of the class described comprising parts which may be readily disassembled for cleaning and readily reassembled. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a vertical longitudinal section through the beverage dispenser of this invention taken on the line 1—1 of Fig. 2;

Fig. 2 is an end view of the beverage dispenser including a longitudinal section through the carbonated water faucet, being taken on line 2—2 of Fig. 1;

Fig. 3 is a transverse section through the carbonated water faucet taken on line 3—3 of Fig. 2;

Fig. 4 is an enlargement of a part of the section through the carbonated water faucet of Fig. 2;

Fig. 5 is a section taken on line 5—5 of Fig. 1 illustrating a detail of the syrup dispensing valve of this invention;

Fig. 6 is an elevation showing one manner of mounting the beverage dispensers of this invention under a counter; and,

Fig. 7 is an elevation illustrating an alternative manner of mounting the beverage dispensers of this invention under a counter.

Similar reference characters indicate corre-

2
sponding parts throughout the several views of the drawings.

Referring now to the drawings, the beverage dispenser of this invention includes a tank, generally designated by reference character 1, containing concentrated beverage syrup. The tank 1 comprises a transparent drum 3, preferably formed of glass or a plastic, the open ends being closed by heads 5 and 7 which are preferably composed of metal but which may be of transparent plastic. The ends of the drum seat in annular recesses 9 and 11 formed adjacent the peripheries of the heads 5 and 7, respectively. Suitable gaskets 13 are disposed between the ends of the drum and the bottoms of recesses 9 and 11. The heads 5 and 7 are clamped against their respective ends of the drum by a centrally disposed through bolt 15 having threaded ends upon which acorn nuts 17 are screwed up against the heads, suitable washers 19 being disposed between the nuts and the heads. The head 7 of tank 1 is formed to provide a filler spout 21 open at its upper end, and a cap 23, of metal or plastic material or the like, is provided for closing the open upper end of the filler spout. The cap 23 may bear suitable indicia indicating the beverage which is to be dispensed. The drum 3 and the heads 5 and 7 may be readily disassembled by removing one or both nuts 17, so that the tank may easily be disassembled for cleaning and reassembled after cleaning.

A syrup dispensing valve, generally designated by reference character 27, is disposed in the head 1 diametrically opposite and below the filler spout 21. This syrup valve 27 comprises a tubular bearing 29 fixed in an aperture in the head 1 and a valve member 31 slidably mounted in the bearing. Bearing 29 extends a short distance into the tank and its inner end is formed as a valve seat 33. A valve head 35 is formed on the inner end of the valve member 31 and has an annular groove therein receiving an annular gasket 37 adapted to engage the valve seat 33 when valve member 31 is moved to the right, as viewed in Fig. 1. Valve member 31 has therein a central bore 39. Radial apertures 41 afford communication between said bore 39 and an annular recess 43 formed in the periphery of valve member 31 adjacent head 35. It will be apparent that when the valve member 31 is moved to the left, as viewed in Fig. 1, to unseat the gasket 37, syrup will flow through the gap between the gasket and the valve seat into the annular recess 43, through apertures 41 into the bore 39 in valve 31, and out of the right-hand end (see arrow, Fig. 1).

The outer end of valve member 31 is formed with a reduced extension 45 and mounted on said extension is a rotary cap 47 having a cylindrical wall 49 telescoped over bearing 29 and adapted to rotate and slide thereon. A nut 51, threaded on the end of extension 45, retains the cap 47 on valve member 31. As particularly illustrated in Fig. 5, the bearing 29 is formed with a peripheral groove having one leg 53 in a plane at right angles to the axis of the valve, and a leg 55 extending at an angle thereto toward the tank 1. A pin 57 secured to cap 47 extends into said groove. The cap 47 is formed at one end of an operating lever 59 having a knob 61 at its other end. A compression spring disc 63 is disposed between the inner end of the cylindrical wall 49 of the cap 47 and the head 1 of the tank. This spring disc 63 biases cap 47 and valve member 31 to the right to the position wherein pin 57 is disposed as shown in Fig. 5 and wherein gasket 37 seats against valve seat 33 to cut off flow of syrup from the tank. The arrangement is such that, when the operating lever 59 is depressed from its Fig. 2 position, the cap 47 is rotated in such manner that pin 57 travels in angular leg 55 of the peripheral groove in the bearing 29, and the cap 47 and valve member 31 move to the left to unseat gasket 37 of the valve head 35. This opens the valve to permit flow of syrup into annular recess 43 and through radial apertures 41 into the bore 39 and out through the outer end of said bore. When the operating lever 59 is released, spring 63 biases cap 47 and valve member 31 to the right to seat gasket 37 of the valve head 35 against valve seat 33 to cut off flow. Cap 47 slides to the right and rotates on bearing 29 during such return movement to return pin 57 to the position shown in Fig. 5. The arrangement is also such that, when the operating lever 59 is moved upward from its position shown in Fig. 2, pin 57 travels in leg 53 of the peripheral groove in bearing 29. Since leg 53 of the groove is in a plane at right angles to the axis of the valve, cap 47 does not slide axially on bearing 29 but merely rotates thereon, consequently such movement of operating lever 59 does not open the valve. The cap 47 is formed with a flat chordal face 65, to function as a cam for purposes to be mentioned subsequently.

In the operation of the dispenser, the operating lever 59 is depressed to open valve 27 to permit syrup to flow out of the tank and also to open a carbonated water faucet, generally designated by reference character 69. This permits flow of carbonated water into the stream of syrup. The syrup and carbonated water mix, and the mixture is caught in a drinking glass or the like (not shown). The operating lever is depressed for the time interval required to fill the drinking glass. It is desirable to dispense uniformly-flavored drinks, and to do so it is necessary that each serving of a particular quantity have the same proportion of syrup therein. The rate of flow of syrup from tank 1, however, is dependent upon the head of syrup in the tank and also upon the extent to which operating lever 59 is depressed. This is because valve 27 functions as a throttle valve and its setting is determined by the position of operating lever 59. Since the time interval required to dispense servings of an equal quantity of carbonated water is the same, it is necessary to depress lever 59 to various positions dependent upon the head of syrup in the tank to insure that the same amount of syrup will flow out of the tank in that interval. If the tank is 75

full, the lever 59 must be depressed only to a certain predetermined limited extent to set the valve 27 to deliver syrup at the proper rate to dispense the required amount of syrup. If, on the other hand, the tank is nearly empty, the lever 59 must be depressed to the ultimate limit in order to open valve 27 sufficiently to deliver the same amount of syrup. Intermediate heads of syrup in the tank require predetermined intermediate settings of operating lever 59 to effect dispensing of syrup at the same rate.

To indicate to the operator the proper setting for lever 59 for a particular head of syrup in the tank 1, the head 1 of the tank 1 is provided with a scale comprising indicia 66 labeled in terms of syrup level. The positions of indicia 66 are so correlated with the positions of the lever 59 that when an edge of the lever coincides with a particular index and the syrup level in tank 1 is that connoted by that particular index the valve 27 is properly set for syrup to flow out of the tank at the proper rate.

The carbonated water faucet 69, illustrated in Figs. 2-4, includes a fitting 71 which is connected to the end of a carbonated water supply pipe (not shown) in fixed position adjacent the tank 1. Adjustably threaded on the forward end of fitting 71 is a cap 75 having a portion 77 provided with a central aperture 79 for passage of carbonated water. The forward end of fitting 71 is counterbored to form a pocket 81 and a beveled annular shoulder 83 therein. The portion 77 of the cap 75 is interiorly counterbored to provide a pocket 85, of the same diameter as pocket 81, and a beveled annular shoulder 87 therein. A tubular element 89, formed of resilient material, preferably such as synthetic rubber, is disposed within pocket 81 and projects forward from the end of fitting 71. The external diameter of the tube 89 is the same as the diameter of pockets 81 and 85 and the ends of the tube are countersunk to seat against the beveled shoulders 83 and 87. The internal wall of the tube 89 is normally cylindrical when the tube is not subjected to axial compression, as illustrated in solid lines in Fig. 4, but by screwing cap 75 up on the end of the fitting the tube 89 may be axially compressed so as to deform the inner wall of the tube to the venturi shape illustrated in solid lines in Fig. 2 and in dotted lines in Fig. 4. When the tube is so compressed it forms a venturi, indicated by reference character 91.

As illustrated in Fig. 4, there is a space between the forward end of fitting 71 and the inner face of the portion 77 of cap 75 when the tube 89 is uncompressed. This permits cap 75 to be screwed up on the end of fitting 71 to the position illustrated by the dotted lines in Fig. 4 so as to compress the tube 89, and permits adjustment of the shape of venturi 91. A vent 93 (Fig. 2) is provided in cap 75 to relieve the pressure in the space within the cap resulting from the screwing up of the cap on the fitting and to prevent this pressure from squeezing tube 89 radially inward and closing off or obstructing the passage therethrough.

The carbonated water faucet also includes a nozzle, generally designated 95, comprising a cylindrical nozzle body 97 having a bore 99 extending inwardly from its rear end of substantially the same diameter as cap 75. The rear end of the nozzle body is telescoped over the cap 75 and may slide thereon, but the clearance is such as substantially to prevent any leakage of carbonated water therebetween. The nozzle body is

guided for sliding movement on the cap by being disposed in a bearing 101 formed on a bracket 103 secured to the head 7 of the tank. The axis of the fitting 71, cap 75, nozzle 95 and its bearing 101 extends at an angle to the vertical and intersects the vertical plane through the outlet of the syrup dispensing valve 27 a short distance below said outlet. Hence the stream of carbonated water flowing from the nozzle merges with the stream of syrup flowing through the outlet shortly after issuing therefrom. The nozzle body 97 is formed with a flange 105 on its forward end having a flat forward surface 107 in engagement with the flat face 65 of cap 47. When operating lever 59 is moved in either direction from its neutral position of Fig. 2, the cap cams the nozzle body upward in its bearing until the cylindrical wall of the cap 47 rides onto the flat surface 107, whereupon the nozzle body is maintained at its upward limit of movement in its bearing.

Nozzle body 97, in addition to the previously mentioned bore 99 therein, is formed with an outlet bore 109 of smaller diameter than bore 99 extending rearwardly in from its forward end and an internal conical surface 111 joining the interior ends of these bores. A streamlining needle member 113 has a cylindrical portion 115 disposed within the larger bore 99 and a conical portion 117 tapering forward therefrom within the internal conical surface 111. This portion 117 also extends into the outlet bore 109. The member 113 is fixed within nozzle body 97 and spaced from the internal wall thereof by means of radial pins 119 extending from the nozzle body into the main body of the needle member. These pass through radial spacing lugs or spot pads 121 formed on the needle member. A valve stem 123 is threaded into an axial bore in the rear face of needle member 113, and is readily removable therefrom. This valve stem extends rearward from the nozzle through the aperture 79 in cap 75 and through the rubber tube 89 into fitting 71, where its end is formed as a valve head 125 having a groove 127. When the fitting is uncoupled from the carbonated water supply pipe, a screw driver may be readily inserted and engaged with the groove to unscrew and remove valve stem 123. The internal diameter of the rubber tube is substantially less than the internal diameter of fitting 71 so that the upper end of the tube forms a valve seat 129 cooperating with the valve head 125. When the nozzle is in the Fig. 2 position, the valve head engages the valve seat to cut off flow through the faucet. When the nozzle is cammed to move upward upon rotation of the operating lever 59, the valve stem and valve head move upward to unseat the head and permit flow.

The forward face of the end portion 77 of fitting 71 is formed with a pair of smooth annular grooves 133 and 135 to provide smooth annular undulating ridges 137 thereon. The rear face of needle member 113 is formed with a pair of smooth annular grooves 139 and 141 to provide smooth annular undulating ridges 143 thereon. When the nozzle body 97 is moved to its upper limit, the ridges 137 are disposed within but spaced from the walls of grooves 139 and 141 and the ridges 143 are disposed within but spaced from the walls of the grooves 133 and 135 so as to provide between aperture 79 in cap 75 and the nozzle passages, a tortuous but smooth radial labyrinth passage for the carbonated water. This reduces its velocity without excessive scrubbing action which might otherwise prematurely release

CO₂ gas. To prevent rotation of the nozzle body 97 on cap 75, a removable screw 147 extends from the nozzle body into a longitudinal slot 149 formed in the cap. This screw also projects through a longitudinal slot 151 in the bearing 101, as shown in Fig. 2. This allows longitudinal movement between 97 and 101. When the valve stem has been removed, the fitting 71 and cap 75 may be readily disassembled from the nozzle by removing screw 147.

A plurality of tanks may be mounted with their axes parallel to each other under a dispensing counter 155. This may be done by suspending such tanks in U-shaped brackets 157 secured at their upper ends to the underside of the counter 155 in any suitable manner, with the filler spouts 21 projecting beyond the edge of the counter, as illustrated in Fig. 6. An alternative tandem mounting of the tanks with a pair of operating levers 59 disposed next to each other and operating in planes perpendicular to the counter is illustrated in Fig. 7. In this arrangement the tanks are supported under a dispensing counter 159 substantially coaxially. This is done by means 25 of brackets 161 having apertured ends received on the ends of the through bolts 15, the acorn nuts 17 being screwed down against the lower ends of said brackets. The upper ends of the brackets are secured to the underside of the counter 159 in any suitable manner. To facilitate filling of the tanks the counter 159 has a gap 163 therein which exposes the filling spout 21 of each of the tanks. It will be noted that in this coaxial manner of mounting the tanks the operating 30 levers of two tanks are disposed adjacent each 35 other for convenience of operation.

The operation of the beverage dispenser is as follows:

If it is desired to dispense a mixed drink, the 40 operator notes the level of syrup in tank 1. Since the drum 3 is transparent, the syrup level may be readily determined merely by inspection. He then depresses operating lever 59 to the proper index 66, dependent upon the level of syrup in tank 1. This opens the syrup dispensing valve 27 the proper amount according to the level of syrup in the tank and syrup flows out of the right-hand end of bore 39 in valve member 31 as shown in Figure 1. Depression of operating 45 lever 59 also causes the nozzle 95 to move upward, as viewed in Fig. 2, to unseat valve head 125 from its seat 129 on the rubber tube 89. Such movement is caused by the camming action of flat face 65 on the cap 47 against the end of the 50 nozzle. When valve head 125 is unseated, carbonated water flows through the venturi 91 formed by the rubber tube 89, through the aperture 79 in the end of cap 75 and then through the tortuous radial passage formed by the cooperating 55 annular grooves and ridges of the end faces of cap 75 and needle member 113. After passing through the tortuous passage, the carbonated water flows in the space between needle member 113 and the internal wall of nozzle body 97 and out through the outlet bore 109 in the forward end thereof. The wall of the conical portion 117 of needle member 113 cooperates with the internal wall of nozzle body 97 to form the nozzle. The carbonated water issuing from the 60 carbonated water faucet 69 is directed thereby into the stream of syrup flowing from the syrup dispensing valve 27 and flows together therewith into a drinking glass or the like which is held by the operator in proper position to receive same.

When the glass has been filled, the operator

releases the operating lever 59. Spring 68 thereupon moves cap 41 outward on the bearing 29 and the cap and operating lever are cammed to rotate back to the neutral position indicated in Figs. 2 and 5. This occurs by reason of the pin 57 riding in the angular leg 65 of the groove in the bearing. Such outward movement of cap 41 pulls valve member 31 outward to cause seating of gasket 37 against valve seat 33 and cut off the flow of syrup. When the operating lever 59 reaches neutral position, the nozzle 95 is no longer subject to the camming action of the cap 41, and the pressure of the carbonated water supply forces valve head 125 against seat 129 to cut off flow of carbonated water, the nozzle thereupon sliding downward in bearing 101 to bring its end 107 into engagement with the flat face 65.

If it is desired to dispense carbonated water only, the operator raises lever 59 from its neutral position indicated in Figs. 2 and 5. Cap 41 rotates clockwise upon bearing 29, as viewed in Fig. 2, but does not slide thereon, since upon such rotation pin 57 travels in the leg 63 of the groove in a plane at right angles to the axis of the valve. The syrup valve 27 therefore does not open and syrup does not flow from the tank, but the nozzle 95 is cammed upward in bearing 101 to unseat valve head 125 as previously described, permitting carbonated water to flow from the nozzle. When the desired quantity of carbonated water has been dispensed, the operator moves operating lever 59 back to neutral position.

An important and advantageous feature of the carbonated water dispensing head is the venturi provided by deforming the tubular rubber member 89. It is highly desirable to avoid turbulent flow of the carbonated water since turbulence increases the release of the carbon dioxide gas therefrom. The venturi 91 reduces the turbulence of the carbonated water by creating streamlined flow thereof. Such flow through the venturi increases the velocity of the carbonated water while causing its pressure to drop. Since it is not desirable to have the carbonated water issue from the carbonated water dispensing head at high velocity the velocity is reduced in the radial tortuous labyrinth passage formed by the annular grooves and ridges on cap 45 and needle member 113.

One of the advantages of the present invention is its adaptability to be easily and readily assembled and disassembled. Sanitation is a necessity in a beverage dispenser and it is highly desirable that a beverage dispenser be of such construction that it may readily be disassembled so that its parts may be cleaned. It will be noted that the component parts of applicant's beverage dispenser are so formed and assembled that disassembly for cleaning is quite simple and does not require any particular skill on the part of the person whose task it is to clean the device. The syrup tank may be easily disassembled simply by removing one or both of the acorn nuts 47 and withdrawing the through bolt 15. When head 7 has been removed, it is a comparatively simple matter to unscrew nut 51 from the end of the valve member 31 and disassemble the syrup valve 27 so that its component parts may be cleaned. The carbonated water faucet 69 may be readily disassembled simply by removing fitting 71 and then unscrewing the valve stem 123 out of needle member 113 and removing screw 147.

Another advantage of the construction is that it provides for the interchangeable use of drums

of different lengths to form tanks of varying capacities. If it is desired to replace an installed tank with one of larger capacity, that tank may be disassembled and its drum 3 replaced by a longer drum and the same heads 5 and 7 may be clamped against the ends of the longer drum by employing a longer through bolt 15 of the proper length.

The drum 3 is preferably made of transparent material such as glass, but it may be made of opaque material and the tank 1 provided with suitable means for indicating the syrup level therein.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A counter dispenser for syrups and the like, comprising a transparent cylinder visibly containing liquid and having a substantially horizontal axis, removable sealed heads on the opposite ends of said cylinder, one of said heads having an upwardly directed inlet and a downwardly located outlet, a removable tension bolt clamping said heads to opposite ends of the cylinder and passing therethrough, liquid flow proportioning control means mounted on said last-named head and controlling said outlet, said flow proportioning control means having a handle and being adapted to dispense different quantities of liquid depending upon the portion of the handle, and indicia on said head with which said control means is visibly coordinated to indicate the amount the control means is to be opened in terms of the amount of visible liquid in the cylinder, said indicia being correlated to the height of liquid head in the cylinder so that, as the liquid head diminishes due to withdrawal of liquid, the resultant slower flow of liquid through the flow controlling means may be compensated by appropriate positioning of the handle to cause a relatively uniform quantity of liquid to be dispensed.

2. A valve comprising a hollow cylindric core of resilient material, axially adjustable means engaging said core at opposite ends for axially compressing said core to produce by deformation an internal Venturi throat, said core extending radially inward on at least one end from one of said adjustable means to provide a valve seat, and a valve engaging said seat.

3. A valve comprising a hollow cylindric core of resilient material, axially adjustable means engaging said core at opposite ends for axially compressing said core to produce by deformation an internal Venturi throat, said core extending radially inward on at least one end from one of said adjustable means to provide a valve seat, a valve head engageable with said seat, and a valve stem carrying said head and extending through the venturi shape of said core.

4. A valve comprising a hollow cylindric core of resilient material, means threaded between one another and engaging said core at opposite ends for axially compressing said core to produce by deformation an internal Venturi throat, said core extending radially inward on at least one end from one of said adjustable means to provide a valve seat, a valve head engageable with

said seat, and a valve stem carrying said head and extending through said core and from one of said adjustable members.

5. A dispenser comprising a tank adapted to contain a first liquid, said tank having an outlet therein, a throttle valve for controlling flow of said first liquid through said outlet, a faucet adjacent said outlet adapted to direct a stream of a second liquid into contact with a stream of said first liquid flowing out of said outlet, a valve in said faucet for controlling flow of said second liquid therethrough, an operating lever movably mounted on said tank for simultaneously operating both of said valves, the position of said lever determining the setting of said throttle valve, and means cooperating with said lever to indicate the proper setting of said throttle valve to obtain substantially the same rate of flow of said first liquid through said outlet for varying levels of liquid in said tank.

6. A dispenser comprising a tank adapted to contain a first liquid, said tank having an outlet therein, a throttle valve for controlling flow of said first liquid through said outlet, a faucet adjacent said outlet adapted to direct a stream of a second liquid into contact with a stream of said first liquid flowing out of said outlet, a valve in said faucet for controlling flow of said second liquid therethrough, an operating lever rotatably mounted on said tank for simultaneously operating both of said valves, the position of said lever determining the setting of said throttle valve, and a scale on said tank comprising indicia labeled in terms of the level of said first liquid in the tank and so correlated with the operating lever that, when said lever is positioned to coincide with the particular index connoting the instant level of liquid in the tank, the throttle valve is so set as to permit substantially the same rate of flow of liquid through said outlet as when the level is different and the lever is positioned to coincide with the index indicating that level.

7. A dispenser comprising a tank adapted to contain a liquid, said tank having an outlet therein, a throttle valve for controlling flow of liquid through said outlet, an operating lever movably mounted on said tank for operating said valve, the position of said lever determining the setting of said valve, and means cooperating with said lever to indicate the proper setting of said valve to obtain substantially the same rate of flow of liquid through said outlet for varying levels of liquid in said tank.

8. A dispenser comprising a tank adapted to contain a liquid, said tank having an outlet therein, a throttle valve for controlling flow of liquid through said outlet, an operating lever rotatably mounted on said tank for operating said valve, the position of said lever determining the setting of said valve, and a scale on said tank comprising indicia labeled in terms of the level of liquid in the tank and so correlated with the operating lever that, when said lever is positioned to coincide with the particular index connoting the instant level of liquid in the tank, the throttle valve is so set as to permit substantially the same rate of flow of liquid through said outlet as when the level is different and the lever is positioned to coincide with the index indicating that level.

9. A dispenser comprising a tank adapted to contain a liquid, said tank having an aperture therein, a bearing fixed in said aperture extending into said tank and projecting outward therefrom, a valve member slidably mounted in said bearing, said valve member having a valve head on the

inner end thereof, a bore extending inward from its outer end to provide a passage for flow of liquid, and at least one radial passage therethrough adapted to establish communication between the interior of the tank and the bore in said valve member when said valve member is moved inward to open position, said valve head being adapted to seat against the inner end of said bearing to cut off flow through said valve member when moved to its outer limit, said bearing being formed with a peripheral groove therein extending at an angle inward toward the tank, a cap rotatably mounted on the outer end of said valve member but axially fixed thereon, a pin fixed in said cap extending into said groove, an operating lever for rotating said cap, said pin traveling in said groove upon rotation of said operating lever in one direction to move said valve member inward to permit flow therethrough, the setting of said valve member being dependent upon the extent of rotation of said operating lever, and means cooperating with said operating lever to indicate the proper setting of said valve member to obtain substantially the same rate of flow of liquid therethrough for varying levels of liquid in said tank.

10. A faucet comprising a fitting adapted to be connected at one end to a source of liquid, a nozzle at the other end of said fitting, a valve in said fitting, and a venturi intermediate said valve and nozzle, said faucet being provided with a tortuous labyrinth fluid passage intermediate said venturi and said nozzle.

11. A faucet comprising a fitting, a nozzle at one end of said fitting, said nozzle comprising a nozzle body telescoped over the end of said fitting, said fitting and nozzle body being relatively axially movable and in substantially fluid-tight relation, a needle member fixed in said nozzle body, a valve stem secured to said needle member and extending therefrom into said fitting, a valve head on said valve stem, and a valve seat within said fitting, said valve head engaging said valve seat when said nozzle body and fitting are relatively moved way from each other to cut off flow through said fitting, said valve head disengaging said valve seat when said nozzle body and fitting are relatively moved toward each other to permit flow through said fitting and nozzle.

12. A faucet comprising a fitting, a cap on one end of said fitting, the outer face of the end of said cap being formed to provide a plurality of annular grooves and ridges, the end of said cap having a central aperture therein, a nozzle body telescoped over said cap so as to be slidable thereon but in substantially fluid-tight relation thereto, a needle member fixed in said nozzle body having a cylindrical portion and a conical portion converging forward therefrom toward the outlet end of said nozzle body, said cylindrical portion having a rear face formed to provide a plurality of annular grooves and ridges cooperating with the annular grooves and ridges of said cap to form a radial labyrinth passage, a valve stem secured to said needle member and extending therefrom into said fitting, a valve head on said valve stem, and a valve seat within said fitting, said valve head engaging said valve seat when said nozzle body and fitting are relatively moved away from each other to cut off flow through said fitting, said valve head disengaging said valve seat when said nozzle body and fitting are relatively moved toward each other to permit flow through said fitting and nozzle.

13. A carbonated water faucet comprising a

fitting, one end of said fitting being connected to a source of carbonated water under pressure, the other end of said fitting being externally threaded and having a counterbore therein forming a pocket having an annular shoulder at the inner end thereof, a tube of resilient material fitted in said pocket and projecting beyond the end of said fitting, the internal diameter of said tube being less than the internal diameter of said fitting whereby the inner end of said tube forms a valve seat within said fitting, a cap threaded on the end of said fitting, the inner face of the end of said cap engaging the outer end of said tube and adapted to compress the tube when screwed down upon the end of said fitting, the outer face of said end of the cap being formed to provide a plurality of annular grooves and ridges, the end of said cap being centrally apertured, a nozzle body telescoped on the cap and adapted to slide thereon but in substantially fluid-tight relation thereto, a needle member fixed within said nozzle body having a cylindrical portion and a conical portion converging forward therefrom toward the outlet end of said nozzle body, said cylindrical portion having a rear face being formed to provide a plurality of annular grooves and ridges cooperating with the annular
